Primary Examiner — Mark A Goodwin*(74) Attorney, Agent, or Firm* — Klintworth & Rozenblat IP LLP(57) **CLAIM**

The ornamental design for a panel of a harvester, as shown and described.

DESCRIPTION

FIG. 1 is a perspective view of a panel of a harvester according to our new design;

FIG. 2 is a first side elevational view thereof;

FIG. 3 is a second side elevational view thereof;

FIG. 4 is a first end elevational view thereof;

FIG. 5 is a second end elevational view thereof;

FIG. 6 is a first plan view thereof; and,

FIG. 7 is a second plan view thereof.

The dash lines depict environment subject matter that forms no part of the claimed design.

1 Claim, 5 Drawing Sheets(56)
